UNITED STATES PATENT OFFICE

WILLIAM MARSHALL, OF DETROIT, MICHIGAN, ASSIGNOR TO BRIGGS MANUFACTURING COMPANY, OF DETROIT, MICHIGAN, A CORPORATION OF MICHIGAN

DOOR CONSTRUCTION

Application filed June 15, 1925. Serial No. 37,323.

This invention relates generally to door constructions, particularly to all metal door constructions for vehicle bodies and consists of certain novel features of construction, combinations and arrangements of parts as will be more fully described and particularly pointed out in the appended claims.

In the accompanying drawings:

Figure 1 is a side elevation of the inner side 10 of the door.

Figure 2 is a perspective view of the door with the outer panel removed.

Figure 3 is a perspective view of the outer panel.

15 Figure 4 is a sectional perspective view of the removable header.

Figure 5 is a sectional view taken on the line 5—5 of Figure 1.

Figure 6 is a sectional view taken on the 20 line 6—6 of Figure 1.

Figure 7 is a sectional view taken on the line 7—7 of Figure 1.

Figure 8 is a sectional view taken on the line 8—8 of Figure 3.

25 Figure 9 is a sectional view taken on the line 9—9 of Figure 3.

Figure 10 is a sectional view taken on the line 10—10 of Figure 2.

Figure 11 is a sectional view taken on the 30 line 11—11 of Figure 2.

Figure 12 is a sectional view taken on the line 12—12 of Figure 1.

Figure 13 is a section taken on the line 13—13 of Figure 1.

35 Figure 14 is a section taken on the line 14—14 of Figure 12.

Referring now to the drawings, the numeral 1 designates a door embodying my invention having an inverted U-shaped frame 2 and the inner and outer sheet metal panels 3 and 4 respectively. As shown, the upright members 5 and 6 respectively of the frame constitute door pillars and are preferably provided at their inner and outer edges with 45 the rearwardly and forwardly extending lateral flanges 7 and 8. The forward pillar 5 is preferably wider than the rear pillar 6, however the forwardly extending flange 8 of the rear pillar is preferably provided for a 50 portion of its length with a lateral flange 9

which projects inwardly and terminates in substantial alignment with the rearwardly projecting flange 8 of the forward pillar 5. The cross bar 10 of the frame 2 constitutes a reinforcing member and is preferably channel-shaped. Any suitable means may be employed for securing this bar 10 to the pillars 5 and 6 respectively. As shown, the outer base portion 11 of the channel bar is provided at its opposite ends with inwardly extending 55 flanges 12 that are preferably welded to the inner faces of the pillars 5 and 6 respectively. The outer panel 4 preferably extends the full length of the pillars and is preferably provided at its upper end with a suitable 60 window opening 13, while the inner panel 3 extends from the lower ends of the pillars to a point in line with the lower edge of the window opening 13 and is preferably provided adjacent to its lower end with a suitable 65 opening 14 to permit access to the space between the panels 3 and 4 respectively. To provide a rigid construction, the inner panel 3 is preferably welded at its forward edge to the inner face of the rearwardly extending 70 flange 8 of the forward pillar 5 and is provided at its rear edge with an outwardly extending flange 15 that is preferably welded to the outer face of the lateral flange portion 75 9 of the rear pillar 6. This inner panel 3 is also provided at its upper and lower edges with the outwardly extending flanges 16 and 17 respectively. The lower flange 17 is preferably wider than the upper flange 16 and terminates at its outer edge in a depending 80 flange 19. Thus, this depending flange 19 cooperates with the forwardly and rearwardly extending flanges of the pillars 5 and 6 to form an attaching frame for the outer panel 85 90 95 100 4. As shown, this outer panel 4 is preferably provided at its side edges with flanges 20 which are return bent around and welded to the flange 7 of the pillars 5 and 6, and is provided at its lower edge with a flange 21 that is return bent around and welded to the depending flange 19 of the inner panel 3. The outer panel 4 is also preferably provided at its upper edge with a narrow flange 22 that extends between the pillars 5 and 6

and projects inwardly over the upper flange 23 of the channel cross bar 10.

As shown, the outer panel 4 is preferably provided at the top, and side edges of the opening 13 with inwardly extending flanges 24 and 26 respectively which cooperate with the flange 16 to form a neat appearance around the window opening 13. As shown, the upper flange 24 constitutes the window header finish strip and conceals the lower flange 27 of the channel cross bar 10, while the lower flange 16 constitutes the window sill and is preferably provided at its inner edge with a return bent portion 28 that terminates in a depending flange 29. The side flanges 26 are parallel to the pillars 5 and 6 respectively and are preferably provided at their inner edges with forwardly and rearwardly lateral offset L-shaped extensions 30 which cooperate with the rearwardly and forwardly extending flange 8 of the pillars 5 and 6 to form channel-shaped runways for a vertically movable glass panel 31. To provide a strong and durable construction, the bases 32 of the extensions 30 are welded to the inner faces of suitable reinforcing strips 33 extending longitudinally of the pillars. As shown, these strips 33 are parallel to the pillars 5 and 6 respectively and are provided at their inner edges from the upper edge of the inner panel 3 to the cross bar 10 with lateral flanges 34 and 35 respectively that are welded to the flange 8 of the pillars 5 and 6. To facilitate this welding operation, the strips 33 and the bases 32 of the extensions 30 are provided with registering slots 36 and 37 respectively for receiving suitable welding apparatus (not shown). Below the window opening 13, the reinforcing strips 33 have channel-shaped portions 38 which are in alignment with the extensions 30 and are adapted to receive the window panel 31 when in lowered position. This window panel 31 may be raised or lowered by any suitable window control mechanism 40 mounted on the inner panel 3 and preferably travels in felt channels 41 which are preferably secured at their upper ends to the strip 33 and are secured at their lower ends in the channel-shaped portions 38 of said strips. Any resilient strip 42 may be secured to the depending flange 29 of the flange 16 to form a weather tight joint with the window panel 31, while a suitable resilient buffer 44 for the lower edge of the glass panel 31 is preferably located at the bottom of the door. This buffer 44 may be any suitable construction but preferably comprises a rubber block 45 having a flanged base 46 that is held by a suitable bracket 47. As shown, this bracket is preferably formed of sheet metal and has a channel-shaped upright portion 48. The sides of this upright portion are preferably provided at their opposite ends with lateral flanges 49 and 50 respectively, while the back 51 of the channel

is preferably provided at its upper end with an inwardly extending flange 52. As shown, the lower flanges 50 of the bracket sides are secured to the flange 17 of the inner panel 3, while the upper flanges 49 overlap the flanges of the base 46 of the block 45 and hold the latter in position.

As shown in Figure 7 of the drawings, the flanges 22 and 24 respectively of the outer panel 4 terminate in line with the outer walls of the extensions 30, thus the glass window panel 31 may be readily inserted into or removed from the felt channels 41 by merely sliding the panel 31 past these flanges 22 and 24 respectively. Normally, the upper ends of the channels 41 are closed by a metal header 54 which is detachably secured by suitable screws 55 between the flanges 22 and 23 respectively. As shown, this header 54 is substantially channel-shape in cross section and is provided at its lower edge throughout a portion of its length with a channel shape portion 56 which holds a suitable resilient channel-shaped strip 57 for receiving the upper edge of the glass panel 31 when in raised position. To facilitate attachment to the door, one wall 58 of the channel portion 56 of the header has a lateral flange 59 that is adapted to fit between the lower flange 27 of the cross bar 10 and an upstanding flange 60 at the inner edge of the panel 24 to position the header.

To provide a neat appearance the inner panel 3 of the door is preferably provided with a suitable cloth lining 61. As shown, this lining 61 is preferably provided with a backing sheet 62, preferably of card board, and is secured to the inner panel 3 by means of the fasteners 63 and finish strips 64 and 65 respectively. The fasteners 63 employed are preferably similar to those disclosed in my co-pending application, Serial No. 734,127 and are located at the lower edge of the inner panel 3, while the strips 64 and 65 respectively are preferably enameled or otherwise finished and are secured to the inner panel 3 at the side edges thereof, preferably by screws 66 which engage nuts 67 anchored in openings in the inner panel 3. The forward strip 64 conceals the joint between the inner panel 3 and flange 8 of the pillar 5 and is provided at its forward edge with an open return bent flange 68 that embraces the forward edge of the lining 61, while the rear strip 65 is mounted on the flange 15 of the inner panel 3 and is provided with the oppositely extending flanges 69 and 70 respectively. As shown, the flange 69 projects rearwardly and conceals the joint between the flange 15 of the inner panel and the flange 8 of the pillar 6, while the flange 70 projects forwardly in spaced relation to the inner face of the inner panel 3 and overlaps the rear edge of the lining 61.

While it is believed that from the foregoing description, the nature and advantages of the

invention will be readily apparent, I desire to have it understood that I do not limit myself to what is herein shown and described and that such changes may be resorted to when desired as fall within the scope of what is claimed.

What I claim as my invention is:

- 5 1. In a door, the combination with a pillar having a lateral flange, of a panel secured to the pillar and provided with a flange having a substantially L-shaped extended portion cooperating with the flange of the pillar to form a channel shaped runway for the glass panel, and a reinforcing strip secured to the base of the extension and having a flange secured to the flange of the pillar, said reinforcing strip having a channel-shaped portion below the panel flange in substantial alignment with the channel shaped runway aforesaid.
- 10 2. In a door, the combination with a pillar having a lateral flange, of a reinforcing strip having a lateral flange secured to the pillar flange and having a channel-shaped portion below its lateral flange, and a glass runway secured to said strip at the upper end thereof and in substantial alignment with said channel-shaped portion.

- 15 3. In a door, the combination with spaced pillars and a channel-shaped cross bar, of a panel secured to said pillars and having a channel-shaped finish strip at its upper end partially enclosing said cross bar, and a header having a portion thereof secured between the walls of said cross bar and finish strip and cooperating with said finish strip to conceal said cross bar.

- 20 4. In a door, the combination with spaced pillars, of a panel secured to said pillars and having a channel-shaped finish strip at its upper end, a channel-shaped cross bar located within said finish strip and having one wall thereof spaced from the corresponding wall of said finish strip, and a header cooperating with said finish strip to conceal said cross bar and having a portion thereof secured between the spaced walls of said cross bar and finish strip.

- 25 5. In a door, the combination with spaced pillars, of a panel secured to said pillars and having a channel-shaped finish strip at its upper end, a channel-shaped cross bar located within said finish strip and having one wall thereof spaced from the corresponding wall of said finish strip, the other wall of said finish strip being provided with a lateral flange, and a header having one end thereof secured between the spaced walls of said cross bar and finish strip and having the other end resting upon the lateral flange of said finish strip.

- 30 6. In a door, the combination with spaced pillars, of a panel secured to said pillars and having a channel-shaped finish strip at its upper end, a channel-shaped cross bar located within said finish strip and having one wall

thereof spaced from the corresponding wall of said finish strip, the other wall of said finish strip being provided with a lateral flange, and a channel-shaped header having one wall thereof secured between the spaced walls of said cross bar and finish strip and having the end portion of its other wall resting upon the lateral flange of said finish strip, said last mentioned header wall being formed with a channel-shaped portion between its ends for receiving the upper edge of a glass panel.

35 7. In a door, a panel having a window opening therein and an inwardly opening channel-shaped portion above said window opening, a frame member extending transversely of said panel and positioned in the channel aforesaid, a separate strip constituting a header for a window having spaced portions secured respectively to the walls of the channel portion of said panel and cooperating therewith to conceal and encase said frame member.

40 8. In a door, a panel having a channel portion, a frame member in said channel portion having a portion disposed in spaced relation to a wall of the channel portion, and a separate strip constituting a header having a portion received in the space between the frame member and the adjacent wall of the channel portion.

45 9. In a door, a panel having a channel portion, a frame member in said channel portion having a portion disposed in spaced relation to a wall of the channel portion, and a separate strip constituting a header having a portion received in the space between the frame member and the adjacent wall of the channel portion, and securing means for said strip extending transversely of said frame member.

In testimony whereof I affix my signature.
WILLIAM MARSHALL.
